UNITED STATES PATENT OFFICE.

OLIVER R. EMIGH, OF WESTMINSTER, MARYLAND, ASSIGNOR TO BALTIMORE ROOFING AND ASBESTOS MANUFACTURING CO., OF WILMINGTON, DELAWARE, AND ASBESTOS, MARYLAND, A CORPORATION OF DELAWARE.

COMPOSITION ROOFING.

1,220,966.

Specification of Letters Patent. Patented Mar. 27, 1917.

Application filed November 10, 1916. Serial No. 130,608.

To all whom it may concern:

Be it known that I, OLIVER R. EMIGH, a citizen of the United States, residing at Westminster, in the county of Carroll and 5 State of Maryland, have invented certain new and useful Improvements in Composition Roofing; and I do hereby declare the following to be a full, clear, and exact description of the invention, such as will enable others skilled in the art to which it 10 appertains to make and use the same.

My invention relates to improvements in the manufacture and method of application of composition roofing material, and it 15 consists in providing a roof covering which is essentially fire and water proof and is very durable in use.

According to my invention I use an under 20 layer of a comparatively thick sheet of asbestos felt above which I place a considerably thicker sheet of rag felt saturated and coated with weather-proofing compounds of mineral oils, such as asphaltums, and these sheets are applied to the roof deck of the 25 building with the asbestos sheet down.

By means of my invention, both in the 30 design of manufacture and method of application, I have combined the essentially important features both of asbestos roofing and rag felt roofing, and eliminated certain objections characteristic to both.

The improvement in rag felt composition 35 roofings accomplished by my invention consists of successfully adding a fire-retarding unit, essentially equal to that secured in an all-asbestos composition roofing, by the addition to the under-side of the rag felt roofing of a heavy sheet of unsaturated asbestos felt to act as a fire screen over the roof deck. 40 By applying this material on the roof deck with the rag felt side to the weather, the asbestos fire screen is held against the deck not only by the nails driven through the roofing, but also by the weight of the rag 45 felt roofing itself, and is preserved from the action of rain, wind and weather by the heavy sheet of rag felt roofing. My invention both as to manufacture of material and method of application obviates unfavorable 50 consequences resulting from any tendency of the saturated rag felt and unsaturated asbestos sheet to separate, due to unequal ratio of expansion and contraction. Should such

separation occur, due to difference in expansion and contraction, no deleterious consequences could result as the asbestos sheet, although separated from the rag felt material, would be held firmly against the roof deck by the nails and weight of the material above it. Such action with the asbestos 55 sheet applied to the weather would result in the asbestos washing or blowing away, thereby eliminating the fire-retarding feature of the material. My invention in this respect relates to a coated rag felt roof permanently insulated on the under-side with fire-resisting asbestos.

My invention is an improvement on all-asbestos roofings because it affords equal fire protection and obviates certain objections inherent in asbestos composition roofings. Because of the nature of asbestos, being a mineral with little tensile strength, composition roofings made exclusively of this material lack the tensile strength of a 75 rag felt roofing, and do not contain the same amount of weather-proofing saturation as an equal weight or thickness of rag felt. It is well known that asbestos will not saturate to the same extent as rag felt, owing to the 80 fact that it is a mineral, and does not possess the capillary attraction of a vegetable or animal fiber, and weather-proofing compound can only be forced around and between the fibers, whereas in rag felt it is 85 absorbed by the capillary action of the fibers themselves. For this reason rag felt will absorb a far larger quantity of water-proofing compound than an equal thickness of asbestos, affording more weather-proof 90 properties to resist the action of the elements. Consequently, asbestos composition roofs cannot be successfully made of a single thickness of felt as is the case with rag felt roofings and it becomes necessary to 95 saturate thin sheets of asbestos and cement two, three or more layers together to secure a material of sufficient thickness. To the top of this is applied a thin sheet of unsaturated asbestos felt, which is commonly 100 exposed to the weather.

All-asbestos composition roofings, even when made in this manner, do not have the tensile strength of a rag felt roofing of equal thickness and frequently tear and blow 105 away when subjected to abnormal wind

pressure. Furthermore, this material frequently tears away from the nails holding same and more frequently the unsaturated thin white sheet of asbestos on top creeps, due to difference in expansion between the saturated and unsaturated material, tears loose from the body of the roofing beneath and blows away, also the thin white sheet when exposed to the weather is subjected to the constant erosion of rain and gradually washes away, thus removing the chief fire-retarding element of the roofing since the saturated asbestos material beneath will burn, owing to its inflammable contents.

My invention is shown in the accompanying drawings in which:

Figure 1 shows a barn roof made of my improved roofing;

Fig. 2 shows one of the sheets of roofing detached, parts being broken away; and

Fig. 3 shows a section on a larger scale of a portion of one of the sheets.

A represents the rag felt roofing material and B represents the asbestos sheet beneath the same.

On the upper surface of the rag felt roofing I apply a weather-proof coating of somewhat higher melting point and less fluid than the saturant beneath, thus constituting what is known in the trade as "rubber" surface or coating, being thus called because it looks like rubber, although there is no rubber contained in the same.

It will be seen that the herein described

manufacture and method of application provides the following advantages:

First, a "rubber" coated rag felt roofing, insulated underneath with a heavy sheet of asbestos, constituting a virtually fire-proof 40 rag felt material;

Second, uniting to a rag felt roofing a fire-resistive feature equal to that of a laminated composition asbestos roofing;

Third, retaining the weather-resistive 45 powers of the best grade of rag felt roofing by virtue of its waterproofing compound;

Fourth, offering a fire-retarding roof of extra efficiency and of far greater tensile strength than a laminated asbestos composition roof;

Fifth, protecting and preserving, through the method of application, the fire resistive properties of the asbestos from the action of sun, rain and wind throughout the entire 55 life of the roof.

Having thus described my invention what I claim and desire to secure by Letters Patent of the United States is:

A composition roofing strip comprising a 60 lower sheet of plain asbestos roofing material, and an upper and thicker layer of rag felt impregnated with asphaltums with a coating of less fluid asphaltum forming the top finish to the strip and imparting a rubber-like appearance thereto, substantially as described.

In testimony whereof, I affix my signature.

OLIVER R. EMIGH.
